UNITED STATES PATENT OFFICE.

CHARLES E. DAVIS, OF CHICAGO, ILLINOIS, ASSIGNOR, BY MESNE ASSIGNMENTS, TO THE GOODMAN MANUFACTURING COMPANY, OF SAME PLACE.

MINING-MACHINE.

SPECIFICATION forming part of Letters Patent No. 671,818, dated April 9, 1901.

Application filed January 18, 1897. Serial No. 619,512. (No model.)

To all whom it may concern:

Be it known that I, CHARLES E. DAVIS, a citizen of the United States, residing at Chicago, in the county of Cook and State of Illinois, have invented certain Improvements in 5 Mining-Machines, of which the following is a specification.

My invention relates to mining-machines, and has for its object to provide a new and 10 improved mining-machine, of which the following is a description, reference being had to the accompanying drawings, wherein—

Figure 1 is a plan view of a mining-machine embodying my invention. Fig. 2 is a 15 side elevation of the same. Fig. 3 is a section on line 3 3, Fig. 1. Fig. 4 is a section on line 4 4, Fig. 1. Fig. 5 is a section on line 5 5, Fig. 1, with parts omitted. Fig. 6 is a section on line 6 6, Fig. 4, with parts omitted.

20 Like letters refer to like parts throughout the several figures.

I have shown my invention in connection 25 with the general type of breast-machine having a stationary and movable frame, the movable frame being provided with a cutter which acts upon the coal or other material operated upon.

As illustrated in the drawings, the stationary frame consists of the pieces A A, connected together by suitable cross-pieces. This stationary frame is provided with the downwardly-projecting parts B, adapted to engage the floor of the mine. At the rear end the frame is provided with the downwardly-projecting parts B' B', provided with the rotatable parts B² on the shafts B³ and preferably so connected with the projecting parts B' that they partly project therefrom. The stationary frame is provided with the jacks C C', at 35 each end thereof, by which it is held in position. The rotatable parts B² preferably have a relative fixed position with relation to the frame and are provided with some suitable locking device, so that they may be held stationary while the machine is being operated.

40 As shown in the drawings, the jack C is provided with a projecting rod C², passing through enlarged openings in the lock C³. Said rod projects over the rotatable parts or rollers B² B², as shown, for example, in Fig. 4. Each 45 of the rotatable parts is preferably provided

with a groove B⁴ opposite the projecting ends of the rods C². When the jack C is in the position shown in Fig. 2—that is, in its holding position—the rod C² is forced into engagement with the rotatable parts B², so as to 55 lock them against rotation. When the jack C is disengaged and lowered to the position shown in Fig. 6, it rests upon the projection C⁴ on the frame and the rod C² is lifted, so as to 60 be disengaged from the rollers B², thereby leaving them free to rotate.

The movable frame D is provided with a cutter-chain D', which is operatively connected with the motor, so that it can be moved 65 along the surface of the material to be cut. This frame is located beneath the stationary frame and is provided with suitable guides, which allow it to be moved back and forward. This frame is so positioned and the cutters 70 on the cutter-chain are so shaped that the bottom of the kerf is substantially on a level with the floor of the mine. In breast-machines as heretofore used a portion of the coal or other material is left projecting above 75 the floor of the mine and must be removed before the machine can be moved forward. By the use of my construction this difficulty is obviated, as the bottom of the kerf is always substantially on a level with the mine-floor. 80 It is of course evident that this result may be obtained by various constructions. As illustrated in the drawings, the movable frame D is provided with the two guiding pieces or strips D², which engage the upwardly-projecting piece D³ on the part B. These strips D² also engage the projections D⁴ on the part B, said strips sliding along as 85 the cutter-carrying frame D is moved. The cutter-carrying frame is provided with the adjusting-screws D⁵, the parts of the frame being movable relatively, so that it can be 90 adjusted to regulate the tension of the chain.

A motor E, of any suitable description, is mounted upon the cutter-carrying frame and 95 connected with the operating parts of the machine. This motor and the accompanying parts rest upon the pieces A A and slide therealong. The armature-shaft of the motor is provided with the pinion E', which engages 100 the gear E². A beveled pinion E³ is rigidly connected with said gear, so as to be operated

thereby, and engages a beveled gear E⁵ on the upright shaft E⁶, mounted in suitable bearings and carrying the sprocket-wheel E⁷, by which the cutting-chain D' is operated. Said 5 shaft is provided with a worm E⁸, which engages a worm-gear E⁹ on the shaft E¹⁰, provided with the pinions F F'. The pinion F engages the gear F² on the shaft G, and the pinion F' engages the internal gear F³ on said 10 shaft, the two gears F² and F³ being loosely mounted upon the shaft. A clutch G' is feathered to the shaft G and is adapted to engage the gear F³ when in a predetermined position and operatively connect it with the 15 shaft. A second clutch G² is connected with the shaft G, so as to slide therealong and is adapted when in a predetermined position to engage the gear F² and connect it with the shaft. The two clutches G' and G² are 20 rigidly connected together by means of the rod G³, so as to move simultaneously. These clutches may be of any desired construction, and the shaft G is made hollow, so as to contain the rod G³, said rod thus being concealed from view. The clutch G² is connected to the shaft G by means of the pin G⁴, which passes through a slot in the shaft, the slot being long enough to allow the clutch to be moved into and out of engagement with 25 the gear F². Said clutch G² is provided with a groove carrying a movable ring G⁵, which is provided with the projections G⁶, engaging the forked or bifurcated lever G⁷, which is used to shift the clutch. This lever is pivotally connected with some part of the frame. As illustrated in the drawings, said lever is connected with the cross-pieces G⁸ (see Fig. 5) by means of the pin G⁹, said pin being formed at its upper end so as to receive a hand-lever 30 by which the clutch may be moved. By this construction I am enabled to do away with an extra idle gear, which would be necessary in order to obtain the proper motion if the gear F² were an external gear. 40 The lever G⁷ is provided with the end G¹⁰, which is so positioned as to engage the projections A' A² on the stationary frame when the motor has reached the limit of its travel in either direction, thereby automatically 45 shifting the clutch. The shaft G is provided with the engaging wheels H H', which engage a suitable rack on the stationary frame, thereby causing a relative movement of the frames when operatively connected with the motor. 50 These racks are made very strong and consist of the pieces A³, which are connected to the pieces A A⁴ of the stationary frame. A series of pins A⁴ are interposed between the pieces A³ and the pieces A, so as to form a 55 rack or ladder, the pins being engaged by the engaging wheels H H'. Each of these pins is preferably surrounded by a sleeve A⁵, as shown in Fig. 4.

I have described these several parts in detail; but it is evident that they may be greatly varied in form, construction, and arrangement without departing from the spirit of

my invention, and I therefore do not wish to be limited to the construction shown.

The use and operation of my invention are as follows: When the machine is in operation, the cutter-carrying frame moves backward and forward along the stationary frame and the cutters on the cutting-chain undermine the coal or other material operated upon. When it is desired to start the machine, the motor is set in motion and the clutch G' is moved so as to engage the gear F³, and the motor drives the cutting-chain and the shaft G. The engaging wheels H H' on the shaft G engage the pins A⁴ of the rack and feed the machine forward. When the machine has reached the limit of its forward movement, the lever G¹⁰ makes contact with the projection A² and the clutch is moved, so as to disengage the clutch G' from the gear F³ and stop the forward movement of the cutter-carrying frame. The motion of said frame is reversed by moving the clutch G² into engagement with the gear F². The motion of said frame is again arrested by the lever G¹⁰ coming in contact with the projection A'. The direction of motion of the cutter-carrying frame can be changed at any intermediate point by moving the clutch mechanism by hand. The manner of connecting these two clutches so that they move as one piece forms a compact and simple device for accomplishing the reversal of the cutter-carrying frame. It will be noticed that the gear F³ is an internal gear and that the pinion F' on the shaft E¹⁰ engages said internal gear. This construction does away with an extra idle gear, which would be necessary in order to obtain the results desired if the gear F³ were an external gear. It will be seen that in the present construction the direction of motion of the pinion F' and of the internal gear F³ is the same, while that of the pinion F and the gear F² is opposite. If the gear F³ were an external gear, it would be necessary to place an intermediate idle gear between the pinion F' and gear F³ in order to rotate said gear and pinion in the same direction.

When the machine is in its working position and the jacks are placed so as to hold it from motion, the rollers B² are held stationary. When it is desired to move the machine, the jacks are lowered, thereby releasing the rollers, and a supporting-piece is placed under said rollers, as shown in Fig. 2, the machine being rolled along said supporting-piece until it has reached the desired position. The motor of course is moved to the position in Fig. 2 when the machine is being moved, so that the greater part of the weight will be upon the rollers.

The tension of the cutting-chain is regulated by means of the adjusting-screws D⁵.

I claim—

1. In a chain breast mining-machine, the combination of the stationary supporting-frame with the movable forwardly-traveling cutter-carrying frame and rotatable part or

- parts mounted on the stationary frame with their axes substantially parallel with the direction in which the cutter-carrying frame moves, whereby the machine may be moved laterally on such rotating parts, and a locking device to lock such rotating parts from rotation when the machine is cutting, such locking part associated with the jacks so that when the jacks are brought into position to hold the machine the rotating parts are automatically locked from rotation.
2. A mining-machine comprising a stationary frame upon which the operating mechanism is supported, and having at its rear end one or more downwardly-projecting shoes or supports, a roller associated with each of said shoes

or supports and mounted on the frame, said roller or rollers adapted to engage a supporting-piece placed beneath the shoe so as to allow the machine to be moved laterally, a holding-jack connected with a rod passing through an enlarged opening or openings in the frame, said rod so positioned as to be opposed to said roller or rollers, the openings through which said rod passes of such size that the rod engages said roller or rollers when the jack is in its operative position and locks said roller or rollers from rotation.
